JOHN D. IHLDER, OF NEW YORK, N. Y., ASSIGNOR TO OTIS ELEVATOR COMPANY, OF JERSEY CITY, NEW JERSEY, A CORPORATION OF NEW JERSEY.

MOTOR-CONTROL SYSTEM.

1,288,418.

Specification of Letters Patent.

Patented Dec. 17, 1918.

Application filed July 22, 1915. Serial No. 41,224.

To all whom it may concern:

Be it known that I, JOHN D. IHLDER, a citizen of the United States, residing in New York, in the county of New York and State 5 of New York, have invented a new and useful Improvement in Motor-Control Systems, of which the following is a specification.

My invention relates in general to the control of electric motors, and is directed more 10 particularly to the electric motors used in operating elevators and the like.

The object of the invention is to provide means whereby the motor may be operated 15 economically and controlled in a practical and most efficient manner, so that the elevator or other appliance connected with the motor will operate with an unusually high degree of economy and safety under all possible operating conditions, and to these ends 20 my invention consists in the features of construction and arrangement having the mode of operation substantially as hereinafter more particularly pointed out.

In the accompanying drawings, Figure 1 25 represents a direct drive or traction elevator installation containing an embodiment of my invention; Fig. 2 is a diagrammatic representation of the various electric circuits; Figs. 3 and 4 are modifications.

Like characters of reference denote similar parts in all of the figures.

Among the prevailing types of electric elevators, the direct drive traction or gearless elevator stands foremost, for not only is it particularly well adapted to the present day demand for high rise at high speed, but it also possesses an unusually high efficiency from a mechanical standpoint in that the transmission of power between the motor 40 and the load is direct and in consequence the transmission losses are low and the static friction or friction of rest is at a minimum. In an elevator of this type, the hoisting motor must of necessity be of lower speed, and of larger size and heavy weight, and hence is more difficult satisfactorily to control than a smaller motor of the geared type having a relatively higher speed with substantially the same horse power output.

The motor of a constant potential direct current electric elevator is required to operate at substantially constant full speed in both directions of rotation under shunt field excitation alone, and the speed variation

should not be permitted to exceed a pre- 55 determined amount even with load conditions which constantly vary and which may be either positive or negative in character. In order to attain this result with any degree of satisfaction, it is the prevailing practice to 60 design the motor so that the ohmic resistance of its armature shall be low, since it is well known that in order that a shunt motor may be substantially self-regulating for changes in load, particular attention must be directed 65 to the resistance of the armature winding. With a self-regulating shunt motor of low armature resistance, it is customary to carry the field magnetization fairly high to the limit that the full load starting current shall 70 not exceed the full load running current, and while this arrangement makes for high efficiency at full running speed of the motor, the consumption of power at starting, stopping and also on slow speed running is very 75 wasteful since the speed of such a motor cannot be controlled to any appreciable extent by varying the field magnetization, hence it becomes necessary to resort to the use of external power consuming resistances 80 connected in series, or in parallel, or both in series and parallel, to the motor armature. From the foregoing it is seen that the present design of motor for a traction elevator is based on considerations of efficiency and 85 speed regulation under full speed running conditions, but where the car is started and stopped in its usual operation at frequent intervals, the motor will frequently not attain full speed before it is stopped again, or at 90 best will not operate at full running speed for any appreciable length of time and hence one derives no great benefit from the high running efficiency and in consequence the average or total efficiency is low which, of 95 course, means a substantial waste of power.

According to my invention, I arrange the motor to run on a field magnetization so low that it may be varied within sufficient limits to keep the power consumption in starting, accelerating and slow speed running substantially the same as that required for full speed running over the same distance of car travel and in this manner I avoid the heavy consumption of power which invariably occurs when the speed of the motor is controlled by external resistances.

For uniform acceleration of a friction-

2
 less elevator machine, the field magnetization must be doubled in starting and accelerating to allow the motor during this period to run on half speed running current, 5 summing the same power that would be used in covering the same distance at full speed at double current, and for friction and other losses which vary for every machine and hatchway installation an additional margin 10 in the field magnetization has to be allowed in order to keep the current to this proportion. Under usual conditions a gearless traction machine will require a variation of 15 $2\frac{1}{2} : 1$ for its field magnetization. A motor 20 of this design permits also of running on a proportional reduction of speed without waste of power. To build a motor along these lines necessitates increasing the size over the one which is designed for small 25 surplus of starting magnetization and high full speed running efficiency. When it is necessary to make the great saving in power consumption and efficiency in starting, slow-speed running, acceleration to full speed and 30 stopping without materially increasing the size as well as the cost of the motor, I employ an unusual large number of turns of armature winding with resultant increase in the armature resistance. This increased 35 resistance results in loss in full speed running efficiency and speed variation, the efficiency loss amounting to a few per cent. at most is of very small importance in comparison with the great gain made at starting, accelerating and slow speed running. In order 40 to overcome the speed variation, I provide two reverse series field windings, one being active on the "up" motion of the elevator car and the other winding being active on the "down" motion of the car, it being well 45 known that a variation of speed of an electric motor due to variations of load may be compensated by means of a reverse series winding of the required strength. The mechanical 50 efficiency of an elevator installation depends in a large degree upon the weight of the counterbalance relatively to that of the car and load, and good practice decrees that the preponderance of weight on the 55 side of the counterbalance should be somewhat less than one half of the full load and the car. With this preferred arrangement of counterbalance, the increase of speed with full load on the down motion will exceed 60 the increase in speed with the empty car going up, while the decrease of speed with the empty car going down will be less than the decrease of speed with full load going up, but since it is generally permissible to 65 allow considerable decrease of speed for a full load going up, it is very undesirable to permit an increase of speed with a full load going down. To enable me to control the permissible variation in speed for the up 65 and down motions, I use a reverse field

winding arranged to give a different magnetizing power for the up and down motions of the elevator. This result may be attained in several ways, one of which is shown in Fig. 2, and comprises two independent reverse field windings so connected and arranged that but one of them is active at a time. This independent action is important since on the up motion it may be permissible to allow a considerable reduction of speed 75 with full load, and the empty car going up represents less than full load counterbalance, hence on the up motion the reverse series winding on the motor may be and preferably is provided with less turns than 80 that used for the down motion.

Other ways of accomplishing a similar result are shown in Figs. 3 and 4, in which the reverse field comprises a single winding with one or more parallel resistances. 85

Referring to the drawings, Fig. 1 represents a typical direct drive or gearless traction elevator comprising an elevator car B and counterbalance weight W which are suspended from opposite ends of the cables B, 90 the latter being driven by frictional engagement with a grooved sheave E rotating with the armature of an electric motor M. A controlling switch D within the car is connected by flexible conductors to a controller C containing the various switches, etc., for controlling the motor circuits. These circuits, together with the controlling switches, are shown diagrammatically in Fig. 2, and 95 comprises a pair of reversing switches R and R', a fast and slow speed switch F, and an accelerating magnet A, the latter being adapted automatically to short-circuit or cut out the motor starting resistance J. As shown in Fig. 2, the motor comprises a shunt field winding G, an extra field winding K, a series field winding S and a reverse series field winding T, the latter comprising 100 two independent parts H and I having an unequal number of turns and permanently connected in the armature circuit of the motor. The operation of the system of control may readily be seen by following out the various circuits. 105

Assuming the operator in the car moves the lever of switch D in a left hand direction so as to engage the switch contact 4, a circuit is thereupon closed to the magnet winding of the reversing switch R and the latter at once closes the proper motor circuits to cause the elevator car to ascend. The motor circuits may be traced from the + main, through the contacts 5 of switch R, to conductor 6, through the contacts 7 of switch R', to and through the motor armature by way of the brushes 8 and 9, through the part H of the reverse series winding T, contacts 10 of the switch R', and by way of the conductor 11, through the series field winding S and starting resistance J to the — main. 110 115 120 125 130

- The shunt field G and extra field K are energized concurrently with the motor armature and receive current directly from the mains, an adjustable resistance L being 5 in series with the extra field winding whereby its magnetizing power may be suitably regulated and controlled. The motor now starts. The operator in the car next moves the car switch lever farther to the left into 10 engagement with the contact 17 which connects the accelerating magnet A in shunt to the armature brushes. As the motor accelerates to slow speed its counter-electro-motive-force rises, and the accelerating magnet 15 operates successively to close the contacts 1, 2 and 3, in the order named to short circuit the starting resistance J and finally the series field winding S, and the motor runs up to normal slow speed, its field magnetization 20 at this time being that due to the resultant action of the shunt field winding, reverse field winding H, and the extra field winding K. The motor may run indefinitely at this reduced speed with high field 25 magnetization and high efficiency with a current consumption of substantially one half of that required for full speed running with the same load. The operator in the car next moves the car switch lever farther 30 to the left into engagement with the contact 12 which causes the magnet switch F to operate and open its contacts 14 and thereby open-circuit the extra field K in one or more steps and the motor runs up to full running 35 speed with the shunt and reverse series field windings G and H excited. Obviously the shunt field winding is of constant excitation while the reverse series winding H tends to assist or oppose the shunt field winding depending upon the direction and amount of 40 current in the reverse winding H, which factor is dependent upon the load and upon whether the preponderance of weight is on the car side of the traction sheave or upon 45 the counterbalance side of the sheave. In other words, if the motor is acting as a motor, and taking current from the mains, the reverse series winding tends to weaken the total field magnetization to increase the 50 speed, while on the other hand if the motor be driven by the load as a generator the current in the reverse series winding will act cumulatively to assist the shunt field winding, thereby increasing the total field 55 magnetization and reducing the speed.
- If the operator wishes to descend, the car switch is moved in a right hand direction so as to operate the reversing switch R' and thereby close a circuit through the lower 60 contacts of the reversing switch R to the motor, the motor armature circuit now being in a direction reverse to what it was before. Upon tracing this circuit, it will be found that the part I of the reverse series winding 65 is now active while the part H of this wind-
- ing is dead, being open-circuited at the contacts 10 of the reversing switch R'. The compensating action due to the reverse series winding I is precisely like that of the winding H, but since the part I contains more 70 turns of winding than the part H, the compensating action of the reverse series is more marked in the case of a descending car than in the case of an ascending car, which action is purposely so arranged and from the 75 stand-point of safety is of great importance.
- In Fig. 3, the reverse series winding T is connected so as to have full power on the down motion of the car, with the reversing switch R' in raised position, whereas on the 80 up motion of the car with the switch R in raised position, the resistance O is connected in parallel, or as a shunt to the reverse field winding T by means of the additional contact 15 of the reversing switch R', hence 85 only a portion of the armature current flows in the reverse winding. With this arrangement, the turns of reverse field winding are more effective on the down motion than on the up motion. 90
- In Fig. 4, both of the reversing switches are provided with additional contacts, such as 15 and 16, controlling resistances O and P, respectively, the resistance O being of less ohmic resistance than the resistance P. 95 With this arrangement, the turns of the reverse winding T are, as in the case of Figs. 2 and 3, more effective on the down motion than on the up motion.
- It will be observed that the series field S 100 is only used in starting the motor, and, while its use in this connection is of advantage in certain cases, it is by no means essential, and in some cases may be omitted entirely. When the unbalanced load is unusually heavy, I prefer to use the series field S, since it is most effective to keep down the starting current and to counteract in starting the demagnetizing effect of the reverse series winding. Obviously my invention 110 is equally well adapted to any standard or special type of shunt, compound or three winding electric motor.
- What I claim is:—
1. An electric elevator comprising a differentially wound electric motor operable at normal speed with low field magnetization, the series field winding acting always differentially to the shunt winding of the motor while the latter is acting as a motor, 115 and cumulatively with the said shunt winding when the motor is acting as a generator, and means to vary the speed of the motor and increase the starting torque by increasing the motor field magnetization. 120
  2. A traction elevator comprising a slow-speed electric motor operable at normal speed with low field magnetization, a differential field winding on the motor for maintaining a substantially uniform speed with 130

- varying loads, and an extra field winding for effecting a reduction in the speed of the motor by increasing the field magnetization. 40
3. An electric elevator comprising an electric motor, a controller for effecting uniform acceleration of the motor, said motor operable at normal speed with low field magnetization, and means to increase the field magnetization and resulting torque at starting to such an amount that the motor will start full load at substantially half full-load full-speed running current. 45
4. A traction elevator comprising a slow-speed electric motor operable at normal speed with low field magnetization, and an extra field winding to vary the field magnetization of the motor and cause it to run at substantially half-speed, with half full-speed running current. 50
5. An electric motor comprising differentially wound field windings, and means for varying the magnetizing power of one of the said windings in accordance with the direction of rotation of the motor, said magnetizing power opposing that of the other winding when starting the motor in either direction. 55
6. An electric motor comprising differentially wound speed compensating windings, and means for rendering active different portions of one of the said windings in accordance with the direction of rotation of the motor armature. 60
7. The combination with an electric motor having a field winding, of a reverse series field winding therefor, and means for rendering active more or less of the turns of said series field winding according to the direction of rotation of the motor armature. 65
8. The combination with an electric motor having a shunt field winding, of a series field winding arranged to oppose said shunt field winding, and means for varying the number of active ampere-turns of said series winding according to the direction of rotation of the motor armature. 70
9. The combination with a differentially wound electric motor, means for reversing the motor, and means controlled by said motor-reversing means for effecting the magnetization of different sections of one of the windings independently. 75
10. The combination with an electric motor having a shunt field winding, of a reverse winding on the motor field, a motor reversing switch, and means for varying the active turns of said reverse winding in accordance with the position of said switch. 80
11. The combination with an electric motor having a shunt field winding, of a reverse winding on the motor field comprising two portions having an unequal number of turns, and a motor reversing switch adapted alternately to energize said portions of reverse winding. 85

In testimony whereof, I have signed my name to this specification in the presence of two subscribing witnesses.

JOHN D. IHLDER.
